UNITED STATES PATENT OFFICE.

ALBERT ANDREWS, OF SPEARFISH, SOUTH DAKOTA.

ENGINE CONSTRUCTION.

Application filed June 29, 1926, Serial No. 119,384, and in Canada December, 1925.

My invention relates to improvements in engines of the expansible fluid or pressure type, and more particularly to those having one or more cylinders arranged parallel to the power shaft.

The primary object of my invention is to provide an improved engine which is simple in construction and composed of few parts, so that it will be durable, efficient and reliable in operation.

Another object of the invention is to provide an engine of this character composed of a plurality of cylinders arranged around the power shaft and so constructed and mounted that any one or more of them may be readily detached as a unit without disturbing the others or rendering them inoperative.

A further object of the invention is to provide an engine of this character in which the reciprocatory motion of the piston is converted to continuous rotary motion of the power shaft by a traveler operating in a continuous cam groove, and in which the parts subject to the greatest wear may be readily adjusted to compensate for the same.

The above and other objects of the invention are accomplished by the constructions illustrated in the accompanying drawings, in which:

Fig. 1 is a plan view of a multiple cylinder engine with some of the parts broken away and in section.

Fig. 2 is a vertical transverse section taken on line B—B of Fig. 1.

Fig. 3 is a detail vertical transverse section taken on line A—A of Fig. 1.

Fig. 4 is a detail sectional view taken on line D—D of Fig. 5.

Fig. 5 is a longitudinal sectional view through an engine having a single cylinder with two pistons operating therein.

Fig. 6 is a face view of the traveler or cam-engaging member showing its V-shaped rib which operates in the cam groove.

In the embodiment of my invention shown in Figs. 1, 2 and 3 of the drawings, I employ a plurality of parallel cylinders 1 arranged around and parallel with a power shaft 12. Any number of these cylinders may be employed and each one together with its valve mechanism and operating parts is a complete unit which may be readily detached from the others without affecting the operation of the latter. This detachable mounting of the cylinders is preferably accomplished by providing end members or

plates 11 which have around their edges curved seats 11^a to receive and engage the cylinders immediately adjacent the flanged ends 1^a of the cylinders and by providing on the cylinders at each end outwardly projecting lugs 1^b, the lugs being bolted as shown in Fig. 2 to curved inwardly bent flanges 11^c formed on the edges of the plates 11 between the curved seats 11^a. The shaft 12 is mounted in suitable bearings 10 arranged centrally in the end plates 11 and it may have one end a pulley 9 or any other means for taking power therefrom. The engine may be supported as a whole by any suitable means, such for example, as the legs or standards 11^d.

Operating in the end portions of each cylinder are pistons 8, the pistons of each pair being connected by a connecting rod 7 which has its central portion enlarged and formed with a transversely extending internally screw-threaded opening 7^a to receive a cross head member 7^b. The latter is cylindrical in form and projects through a longitudinal slot 1^d in the cylinder 1 and it has an externally threaded portion which screws in the opening 7^a to permit adjustment of the cross head transversely of the piston rod. The cross head 7^b is locked in adjusted position by providing on its inner end a reduced threaded portion 7^c engaged by lock nuts 7^d which screw up against one edge of the piston rod as shown in Fig. 3. The outer end of the cross head 90 member 7^b is formed with a cylindrical socket 7^e to receive an oscillating pin 4, and this outer portion beyond the slot 1^d in the cylinder carries one race-way for a series of anti-friction bearing balls 5^a, the other race 95 for which is in an anti-friction ring or roller 5 mounted to travel between two parallel guideways 1^e mounted on the cylinder adjacent the slot 1^d. The pin 4 has on its outer end an oscillating block or 100 traveler 4^a which is formed on its outer face with a transversely extending V-shaped rib 4^b to engage and travel in a continuous cam groove 3^a formed on the outer surface of a cylindrical enlargement 3 keyed or otherwise secured to the shaft 12. The cam groove 3^a passes around the enlargement 3 a plurality of times, preferably twice, so that this groove has substantially the form of a figure 8. By this arrangement, it 105 will be seen that on each complete movement of the pistons 8, the shaft 12 will be

caused to rotate twice. It will therefore be seen that this cam and traveler connection between the pistons and the power shaft will double the number of revolutions of the shaft with the same piston travel required to rotate the usual crank shaft. The above mentioned adjustment of the cross head member 7^b in the piston rod permits the pin 4 to be advanced when any appreciable wear occurs on parts 3^a and 4^b, the V-shape of the groove 3^a permitting the V-shaped rib 4^b to move deeper into it during such adjustment. The mechanism above described for converting the reciprocatory motion of one pair of pistons to the rotary motion of the power shaft applies of course to all of the cylinder units which may be used in the engine, the one cam groove 2^a serving all of these units.

20 Any suitable valve mechanisms may be employed at the ends of the cylinders, but in Fig. 1 I have shown slide valves with suitable ports co-acting with ports in the ends of the cylinder and the valve housing. 25 When slide valves such as 16^a are employed, the two slide valves for each cylinder are connected by a slidable rod 15, the connection being preferably adjustable as shown in Fig. 5. Each of the rods 15 carries a cam 30 traveler or member 20^a which may be similar in construction to parts shown in Fig. 3. The swiveled or oscillating pin of the member 20^a has a V-shaped rib to enter a continuous V-shaped cam groove 2^a formed in a 35 second cylindrical enlargement 2 on the shaft 12 as shown in Fig. 1. The cam groove 2^a also extends twice around the shaft and is in the form of a figure 8 although this valve operating cam groove has short cross 40 over portions connected by long straight portions so that the valves will be held in their proper positions during the necessary inlet and exhaust periods of the operation of the engine. The member 20^a may be adjustably 45 mounted on the valve rod 15 as shown in Fig. 5 to permit of the proper timing of the valve. It will be seen on reference to Fig. 1 that the one cam groove 2^a serves to control all of the valves for the several cylinders when two or more cylinders are used.

50 In Fig. 5 of the drawings, I have shown an engine with a single cylinder having two pistons operating therein. This engine is substantially identical with any one of the 55 units of the multiple cylinder engine shown in Figs. 1, 2 and 3. The cylinder 1^a is suitably supported by end plates or members 11^a having bearings 10^a for the shaft 12^a. On this shaft are the enlargements 3^b and 2^a having the cam grooves similar to those shown in Fig. 1. The pistons 18 in the cylinder are connected by the rod 7^a which has in it the adjustable cross head member 7^b corresponding to 7^b in Fig. 3. This cross head carries the oscillating traveler or block which

operates in the continuous cam groove of enlargement 3^b. The valves 16^b are connected by the rods 15 and are preferably adjustably connected to such rod by threading the ends of the latter to screw into sockets 70 in the valves and providing lock nuts as shown in Fig. 5. Adjustably connected to the valve rod 15 is the housing or casing of a swiveled or oscillating traveler 20^c which co-acts with the cam on the enlargement 75 2^c. The housing 20^b is adjustably connected to the valve rod 15 by having a threaded portion of such valve extend through an opening in the housing and employing nuts 20^e—20^e on such threaded portion of the rod on opposite sides of the housing as shown in Fig. 5. This construction permits of the proper timing of the valves.

80 From the foregoing, it will be seen that an efficient and desirable engine mechanism results from the construction illustrated and described, but it will be understood that variations in construction may be made within the spirit and scope of the invention 90 as claimed.

I claim:—

1. An engine comprising a shaft, two end plates having centrally arranged bearings for the shaft and having their edges formed with curved seats and inturned flanges, a plurality of parallel cylinders arranged around the shaft and having flanged ends detachably engaged with said seats, the cylinders also having at their intermediate portions longitudinal slots and at their end portions outwardly projecting lugs detachably secured to the inturned flanges on the end plates, guide-ways on the cylinders adjacent their slots, a pair of pistons in each cylinder, a piston rod connecting the pistons of each pair, cross heads on the piston rods and slidably in the guide-ways, a cylindrical enlargement on the shaft having a continuous cam groove extending a plurality of times 100 around the enlargement, a traveler on each cross head to engage the cam groove, a valve mechanism at each end of each cylinder and detachable therewith, a slidable valve-operating rod for the valve mechanisms of each cylinder, a second cylindrical enlargement on the shaft and having a continuous cam groove, and members on said valve rods to engage the last-mentioned 110 groove.

120 2. An engine comprising a rotatably mounted shaft, a cylinder supported parallel to the shaft and having its central portion facing the shaft formed with a longitudinal slot, opposed guide-ways adjacent the slot, a pair of pistons in the cylinder, a connecting rod uniting the pistons and formed with a transverse opening, a cross head adjustable in said opening, a valve mechanism at each end of the cylinder, a slidable valve-

operating rod connecting the valve mechanisms, a cylindrical enlargement on the shaft formed with a continuous V-shaped cam groove extending a plurality of times around 5 the enlargement, a V-shaped traveler on the cross head to engage the cam groove, a second cylindrical enlargement on the shaft formed with a continuous cam groove, and a member on the valve rod to engage the 10 last mentioned cam groove.

3. In an engine, a rotatably mounted shaft having an enlargement formed with a continuous cam groove of V-shape in cross section, a cylinder mounted parallel to the 15 shaft, a piston in the cylinder, a reciprocating piston rod connected to the piston and formed with a transverse screw-threaded opening, spaced guide-ways parallel with

the cylinder, a cross head member having a cylindrical socket in one end and a reduced 20 screw-threaded portion at its other end, a portion of said member being screw-threaded for adjustment in the opening in the piston rod, a nut on the reduced end of said member to engage one edge of the piston 25 rod, an anti-friction bearing ring on the socketed end of said member for rolling contact with the guide-ways, an oscillating pin in the socket of said member and having at its outer end a traveler block with a V- 30 shaped rib to enter the cam-groove for the purpose set forth.

In testimony whereof I have hereunto affixed my signature.

ALBERT ANDREWS.
